UNITED STATES PATENT OFFICE.

JAMES W. ARROWSMITH, OF MORRISTOWN, NEW JERSEY.

BUNION SHIELD AND CORRECTOR.

1,103,465.

Specification of Letters Patent. Patented July 14, 1914.

Application filed November 1, 1911. Serial No. 657,955.

To all whom it may concern:

Be it known that I, JAMES W. ARROWSMITH, a citizen of the United States, and a resident of Morristown, in the county of 5 Morris and State of New Jersey, have invented certain new and useful Improvements in Bunion Shields and Correctors, of which the following is a specification.

The improvements relate to devices for 10 the purpose of protecting and treating bunions and similar deformities of the human foot, and their objects are, among others, to provide a device of this character which will be simple, strong and durable in construction, 15 and easy of manipulation and which will will protect the affected parts from irritation due to friction or pressure on the most sensitive points, permit the treatment of the same by medication or otherwise and at the 20 same time provide for the correction of the deformity by the gradual restoration of the parts to their normal position and relation.

The invention consists in the construction, combination and arrangement hereinafter 25 described and claimed and illustrated in the accompanying drawings.

In the said drawings Figure 1 is a plan of the forward portion of a human foot with a bunion shield and corrector embodying 30 the improvements applied thereto. Fig. 2 is a perspective of the bunion shield and corrector detached from the foot. Fig. 3 is a vertical section on the line 3—3 of Fig. 2 looking in the direction indicated by 35 the arrow.

A is the sole-piece of the device adapted to lie beneath the ball of the foot and to expand to a point beyond the joint of the phalanges of the great, first, second and third 40 toes. Near its forward end it is provided with upright hollow posts B and C, made of stiff leather or other desirable material and provided with bottom flanges B' and C', respectively, by means of which they are 45 securely and rigidly fastened to the sole-piece. These posts are of greater length than width, and are adapted to receive when it is desired a filling of absorbent cotton or other suitable substance to give them a certain 50 degree of elasticity, and also to expand them so as to increase the pressure on the adjacent toes. By placing the device on the foot with these posts collapsed and then filling them from time to time they may be 55 caused to expand and exert a gradually in-

creasing pressure tending to restore the toes to their normal position. The sole-piece is also provided with an extension E which may be made integral therewith or of a piece of more flexible material and extends 60 up around the side of the foot and over the upper surface thereof a short distance along the metatarsal to the first phalanx of the great toe. A bulged portion or protuberance E' is provided in this side portion for 65 the purpose of shaping it to the tuberosity commonly known as the bunion.

Within the turned-up side portion E is a pad or cushion F covered by a layer of adhesive plaster or other tough flexible substance F'. The cushion may be of absorbent cotton, sponge rubber or other compressible material and it and the covering F' may be medicated if desired.

In operation the device is placed on the 75 foot, with the side portion E covering the bunion, the post or toe brace B between the great toe and the second toe and the similar post C between the second and third toes. It will be seen that these posts are adjacent 80 to the joints of the phalanges and that the cushion F is opposite the joint between the first metatarsal and the phalanx. Now as a bunion is usually produced by shoes which are too narrow at the toe or too short for the 85 foot and tend to force the great toe inward and thus cause the said joint of the phalanx and metatarsal to protrude, in correcting this deformity it is desirable to gradually and without causing unnecessary pain to the 90 wearer to cause the great toe to move outward and at the same time bring the said joint inward to its proper position. Therefore, by packing the hollow toe braces and exerting a slight pressure against the said 95 joint this may be accomplished, and it is to effectuate this treatment that the improvements are largely intended. The post between the second and third toes is also useful in preventing the second toe from being 100 displaced when the post B is expanded, as well as in correcting any displacement of the bones of that toe which may exist.

In order to maintain an increased pressure on the joint adjacent to the bunion a 105 strap or girdle G, secured to the sole piece and passing around over the top of the foot is provided, and this strap or girdle is made of elastic material which causes it to exert a constant but yielding pressure tending to 110

restore the affected joint to its normal position. This strap or girdle also assists in holding the shield and corrector in position.

What I claim as new is:

- 5 1. In a device of the character described the combination of a sole piece extending from the metatarsals to the forward phalanx of the great toe, an upright piece mounted thereon at its forward part, and an extension at the side thereof extending upward and over the joint of the great toe phalanx and the first metatarsal, and an expansible band secured to the said sole piece and adapted to extend around the side piece and 10 the foot of the wearer, whereby inward pressure is exerted on said joint, and means for causing the said upright piece to exert outward pressure on the inner side of the great toe.
- 15 2. In a device of the character described, the combination of a sole piece having an

upward extension at the metatarso-phalangeal joint adapted to be maintained in contact with the outside of the foot at said joint and an upward extension at the inside of the great toe, the said extension outside the foot at the said joint terminating back of the phalangeal great toe joint so as to permit the toe to move freely outward independently thereof, and the said upward extension inside the great toe consisting of an expansible tube having an opening therein, whereby it may receive an expansive filling and be caused to exert an increasing outward pressure on the great toe. 25 30 35

Witness my hand this 24th day of October 1911, at the city of New York, in the county and State of New York.

JAMES W. ARROWSMITH.
